UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SEWING-MACHINE.

1,251,873.

Specification of Letters Patent.

Patented Jan. 1, 1918.

Application filed November 25, 1914. Serial No. 873,872.

To all whom it may concern:

Be it known that I, ALBERT H. DE VOE, a citizen of the United States, residing at Westfield, in the county of Union and State 5 of New Jersey, have invented certain new and useful Improvements in Sewing-Machines, of which the following is a specification, reference being had therein to the accompanying drawings.

- 10 This invention relates to an improvement in that class of sewing machines designed for sewing tubular articles, such as the sleeves of garments, in such manner that the article is delivered from the work-supporting member of the machine by the action of the feeding mechanism as the stitching proceeds. The improvement has for one of its chief objects the construction of the machine-frame in such manner as to facilitate the 15 handling of the work and its delivery to the stitch-forming mechanism under advantageous conditions. It has for another object to provide a simple and effective mechanism for operation upon the work.
- 20 The machine-frame is preferably constructed in general conformity with that shown and described in my pending application Serial No. 852,345, filed July 22, 1914, with the work-supporting member disposed 25 transversely to and laterally offset from the standard with which it is connected by means spaced above the base of the standard. That portion of the work-supporting member nearest its connection with the standard is preferably contracted in girth, and may 30 be made both of less width and less depth than the opposite end portion provided with the feeding and stitching means, in order to allow ample slack in the material to be 35 presented to the stitch-forming mechanism and to accommodate the operator's fingers 40 in manipulating it on its way to the stitching mechanism.

The uncontracted portion of the work- 45 supporting member is preferably formed with reciprocally and laterally swinging sections each sustaining a loop-taker permanently connected by suitable gearing with a driving gear upon a shaft mounted in fixed 50 bearings of the work-supporting member and itself connected through a suitable train of gearing, including an intermediate shaft, with the main-shaft journaled within a laterally extending frame-member connecting the upper portion of the standard

with the laterally offset work-supporting member. These loop-takers coöperate with needles carried by a vibratory needle-carrier having a sliding pin-and-socket connection with a sleeve embracing an eccentric upon 60 the adjacent extremity of the main-shaft from which the needles derive their reciprocatory movements.

The feeding mechanism preferably comprises a rock-lever mounted upon a fixed fulcrum and having journaled therein lengthwise thereof a slide-bar sustaining the feed-dog, the rock-lever and slide-bar having independent connections with the said sleeve by means of which the needle-bar actuating 65 eccentric is caused to impart operative work-advancing and rising-and-falling movements to the feed-dog. The needle-actuating eccentric preferably carries a crank-pin in its outer face fitted within an aperture of 70 a socket member embracing the shank of a needle-thread take-up arm mounted upon a fixed fulcrum adjacent the junction of the intermediate frame-member and the work- 75 supporting member.

Journalized within and longitudinally of the intermediate frame-member is a rock-shaft from which is laterally extended, preferably in a direction inclined to the length of the work-supporting member, a rigid arm 80 carrying the presser-foot. As the vibratory needle-carrying arm is disposed above and lengthwise of the work-supporting member, it is desirable that the operator's vision be further obstructed as little as possible by 85 other elements of the mechanism, and by extending the presser-foot supporting arm at a lateral inclination with the work-supporting member and the needle-carrying arm, this element is brought to one side of 90 the operator's range of view of the work which is downwardly inclined over the end of the work-supporting member connected with the intermediate frame-member.

In the accompanying drawings, Figure 1 100 is a front elevation, with the frame in section, and Fig. 2 a side elevation, of a machine constructed with the present improvements. Fig. 3 is a rear elevation of the machine, with the rearward portion of the work-supporting member partly in section, and Fig. 4 a sectional plan view of the frame standard with the presser-foot lifting means. Fig. 5 is a plan of the machine. Fig. 6 is a 105 sectional elevation of the work-supporting 110

member and the parts carried thereby, Fig. 7 a plan of the work-supporting member, partly in section, with certain parts carried thereby, and Fig. 7^a a detail sectional view 5 of an element of the loop-taker adjusting means. Fig. 8 is a side view of the needle and feed mechanisms.

As represented in the drawings, the frame 10 comprises the hollow upright standard 1 having the flanged base 2 and sustaining at its upper end the lateral arm comprising the tubular member 3 terminating in the downwardly inclined extension 3' connected with the top of the horizontal work-supporting 15 member 4 depending therefrom. At the junction of the extension 3' with the member 4 is a cavity 3'' for housing certain of the operative parts, this cavity being partially closed by means of the end-cap 5. The 20 otherwise oval body portion of the standard is shown (see particularly Figs. 1 and 4) flattened at 1' on the front and inner side to afford clearance for the arm of the operator beneath the intermediate frame-member 25 3 in adjusting the work upon the work-supporting member immediately in advance of its junction with the intermediate frame-member.

The outer or free end portion 4 of the 30 work-supporting member is connected with the intermediate frame member by means of a contracted portion 4', the outer uncontracted portion being cut away laterally at the upper side to form at the lower side the 35 supporting tongue 4'', above which are pivotally mounted by means of the vertical stud-pins 6 the laterally swinging sections 7. As shown in the drawings, the contracted portion of the work-supporting member is 40 both narrower and of less depth than the uncontracted portion within which the stitch-forming elements coöperate in the production of the stitching.

The uncontracted portion of the work-supporting arm is made of sufficient width 45 and depth to accommodate the loop-takers and the feed-dog with their accessories, but is made as small as practicable to accommodate the smallest tubular portions of garments to be stitched. The inner contracted portion of the work-supporting member, arranged between the uncontracted portion and the intermediate frame-member, is made 50 sufficiently smaller than the adjacent portion to permit ample clearance for the fingers of the operator in manipulating the fabric around the same preparatory to its presentation to the stitch-forming mechanism. By this means, the operator is enabled 55 to handle the work with ease and is not cramped by necessity of forming the garment for stitching from the outer face of the fabric, which would be the case if the forward portion of the work-supporting 60 member were uncontracted.

The throat-plate 8 is secured upon the top of the post 4'' at one end by means of the screw 9 and upon the upper face of the member 4 at the opposite end by means of the screws 10. The throat-plate is provided 70 with the usual feed-dog opening 11 and needle-apertures adjacent the same.

Mounted within the intermediate frame-member 3 and extending across the upper portion of the standard 1 is the main-shaft 12 carrying within the upper portion of the standard the grooved belt-wheel 13 embraced by the driving belt 14 extending from the source of power upwardly through the standard. The main-shaft has secured 75 theron at its outer end, and adjacent its connection with the work-supporting member, the actuating eccentric 15 for imparting operative movements to the needles and the feeding mechanism. Adjacent the eccentric 15 the main-shaft has fixed thereon a bevel pinion 16 meshing with a similar pinion 17 upon the short intermediate shaft 18 which is in turn connected by means of the intermeshing bevel pinions 19 and 20 with 80 the loop-taker actuating shaft 21 journaled within and longitudinally of the work-supporting arm and having fixed upon its outer extremity the driving gear 22.

Intermeshing with the driving gear 22 are 85 the pinions 23 each fixed upon a short shaft 24 journaled in bearing bushings 25 of the respective laterally swinging sections 7. The stud-pins 6 upon which the sections 7 are fulcrumed have their axes preferably in 90 intersecting relation with the pitch line of the driving gear with the respective pinions 23 and at the rear face of the latter, so that in the swinging of such sections between operative and retracted positions the pinions 105 will be maintained permanently in mesh with the driving gear, as represented in Fig. 7.

Each shaft 24 has fixed thereon a spiral gear 26 meshing with a similar gear 27 110 which is shown formed upon the hub of the cup-shaped loop-taker 28. The loop-taker hub is mounted upon the fixed horizontal fulcrum stud-screw 29 tapped into the 115 adjustably sustained holding plate 30. The plate 30 is formed on its inner face with an integral stud 31 and it carries a second stud 32 parallel therewith having near its outer end a flange 33 beyond which is an eccentric necked portion 34 closely embraced by the 120 side edges of a slot extending lengthwise of the plate 30, the stud 32 being held in position by means of the clamp-screw 35 between whose head and the flange 33 the surrounding portion of the plate 30 is clamped.

The studs 31 and 32 are slidingly fitted 125 within suitable apertures in the body of the section 7 within which they are secured by set-screws 36 in the desired position of end-wise adjustment of the gear 27 for the po- 130

sitioning of the loop-taker to secure the desired gage of the seams. By loosening the set-screws 36 and turning the stud 32 through the clamp-screw 35, the stud 32 may 5 be shifted transversely of its length, thereby raising or lowering the corresponding end of the holding plate 30 and correspondingly adjusting the position of the loop-taker and its connected spiral gear for taking up wear 10 or for other purposes.

The loop-takers represented in the drawings are of a well-known type, being formed with a loop-taking beak in the outer end and having fitted within the same a thread-case 37 provided with a bobbin 38. As 15 shown and described more fully in my pending application Serial No. 852,345, each of the sections 7 is provided with a holding plate or hanger 39 pivoted thereto at the lower end and provided with a lateral arm 40 adapted for engagement with the hooked end 41 of a spring 42 secured in a longitudinal channel of the pin 43 mounted within a suitable transverse aperture of the section 25 7 in which it is adjustably secured by means of the set-screw 44 (Fig. 3).

The pin 43 has a transverse aperture entered by the reduced extremity of the plunger-pin 45 fitted within a suitable aperture of the section 7 and resting upon the spring 42. The section 7 having been retracted as represented in the lower part of Fig. 7, by depressing the plunger-pin 45 the spring 42 is deflected to disengage it from 35 the hanger 39 which may be swung outwardly for access to the thread-cavity of the loop-taker.

Each of the sections 7 is provided with a spring-catch 46 whose hooked operative extremity 47 is adapted for engagement with the shoulder of one of the latch-plates 48 secured by means of screws 49 adjustably in position upon the post 4". These sections are normally held in operative position by 45 engagement of the spring-catches with their respective catch-plates, and may be retracted for introduction and removal of the lower thread supply to the loop-takers by pressing inwardly the spring-catches for 50 their disengagement from the shouldered catch-plates.

Secured upon the inner face of the end-cap 5 by means of the screw 50 is a fulcrum-stud 51 disposed above the work-supporting member and near its junction with the intermediate frame-member. Mounted upon the stud 51 and maintained in position thereon by the cap-screw 52 is the hub 53 of the needle-carrying arm 54 provided in its outer end portion with a socket in which is secured by means of the set-screw 55 the shank 56 of the needle-clamp 57 which carries in practice two eye-pointed needles 58 co-operating with the loop-takers 28 in the production of 65 stitches.

The hub 53 is formed with the rearwardly extending boss 59 sustaining the pin 60 which is slidingly fitted within a tangential socket or aperture of the boss 61 formed upon the lower side of the sleeve 62 which is in turn fitted upon the actuating eccentric 15 of the main-shaft. The needle-arm 54 derives, from the described pin-and-socket connection with the sleeve 62 embracing the actuating eccentric, vibratory movements 70 from which the needles 58 derive their substantially rectilinear reciprocations.

The hub of the needle-arm 54 has upon one side of said arm a rearward extension 63 to which is pivotally connected one end of a link 64 whose opposite end is similarly connected with the rearwardly extending arm of a rock-lever 65 mounted upon the fixed transverse fulcrum-pin 66 and formed with a longitudinally extending tubular member 67 disposed above the fulcrum-pin. Slidingly fitted within the member 67 is the tubular bar 68 constituting the shank of the feed-dog 69.

Secured by means of a set-screw 70 within a socket in the forward end of the slide-bar 68 is one end of a flexible rod 71 whose opposite end is secured within the rocking stud-pin 72 upon the adjustable block 73 fitted within a lateral recess of the feed rock-lever 74. The lever 74 is mounted upon the fulcrum-stud 75 tapped into the cap-plate 5 and secured in position by the jam-nut 75'. The block 73 is secured for adjustment toward and from the fulcrum 75 by means of the screw 76 passing through an elongated slot of the lever 74 and tapped into said block 73 which may be adjusted by loosening the screw 76 and shifting the block and retightening said screw. The upper arm of the lever 74 is formed as a slide-pin 77 which is fitted within a lateral tubular boss or socket 78 of a collar 79 embracing the shouldered crank-pin 80 which is secured in the split boss 81 of the sleeve 62.

From its described connections, the feed-dog receives its to-and-fro or work-advancing movements from the sleeve 62 embracing the common actuating eccentric 15; while tilting movements are imparted to the rock-lever 65, and hence rising-and-falling movements are communicated to the feed-dog 60 by the link connection 64 of the rock-lever with the needle-lever, which in turn derives its operative movements from the described pin-and-socket connection with the sleeve 62. Hence, the reciprocating movements of the needles and both the work-advancing and the rising-and-falling movements of the feed-dog are derived from 120 the common actuating element upon the shaft 12.

Tapped into the cap-plate 5 in which it is secured by the jam-nut 82 is the fulcrum-stud 83 upon which is mounted the sleeve 84.

having a split socket 84' in which is clamped by means of the screw 85 the take-up arm 86 having the reduced and backwardly bent portion 87 provided with the usual thread-eye. Slidingly fitted upon the straight cylindrical portion of the arm 86 is a sleeve 88 formed with a lateral lug 89 apertured to receive the crank-stud 90 which is tapped into the outer face of the actuating eccentric 15.

In the rotation of the eccentric 15 with the shaft, the crank-stud 90 is carried in a circular path and thereby communicates to the take-up arm through the described 15 connections vibratory movements upon the fulcrum-stud 83. It will thus be seen that the reciprocation of the needles, the operative movements of the feed-dog and the vibratory movements of the take-up arm are 20 all derived from operative connections with the actuating element 15 upon the main-shaft, and that the timing of these several members is therefore fixed for all adjustments and under all operative conditions of 25 the machine.

Opposed to the feed-dog is the usual presser-foot composed in the present instance of the pressure-plate 91 pivotally connected with the lower end of the shank 92 whose 30 upper end is fitted within the transverse boss 93 of the laterally extending arm 94 having a hub 95 secured by means of the set-screw 96 upon the rock-shaft 97 which is journaled within and longitudinally of 35 the intermediate frame member 3 parallel with the main-shaft. The presser-foot carrying arm 94 extends from a position intermediate the ends of the frame-member 3 in a direction inclined to the work-supporting member 4, 4', as represented particularly in Fig. 5, in order to avoid obstructing the view of the operator in looking across the extremity of the member 3 toward the stitching position.

45 The rock-shaft 97 has secured upon its rearward end a collar 98 from which extends upwardly the laterally offset tappet-arm 99, and from which depends a second arm 100. The forward face of the tappet-arm 99 is 50 engaged by one end of a pin 101 whose opposite end rests in the bottom of a socket in the adjacent extremity of the plunger-pin 102 which is fitted within the transverse tubular boss 103 upon the top of the stand- 55 ard 1.

Surrounding the pin 102 is a spring 104 of which one end rests upon the collar 102 of the pin 102 and the other against the inner end of the bushing sleeve 105 entering 60 the opposite end of the boss 103. The spring 104 acts through the pins 102 and 101 upon the tappet-arm 99 and thence through the rock-shaft and lateral arm 94 to thrust the presser-foot downward upon the work-support, and the stress of the spring is adapted 65

to be regulated in a manner well-known by means of the bushing sleeve 105.

The standard 1 is provided near its base with the spaced and apertured lugs 106 to receive the fulcrum-pin 107 upon which 70 is mounted the hub 108 of a rock-lever having one arm 109 extending inwardly through the wall of the standard where it is provided with a roller-stud 110 adapted for engagement with one edge of the depending rock-shaft arm 100, as represented in Fig. 4. An oppositely extending arm 111 of said rock-lever is formed with an eye to receive the hooked extremity 112 of the treadle rod 113 by means of which the rock-lever 108 80 109 111 may be operated to press the arm 100 laterally and thereby rock the shaft 97 in opposition to the spring 104 to lift the presser-foot. In preparing the machine for operation, the two needle-threads are led 85 from the source of supply through the apertured lugs 114 of the tension-supporting plate 115 and thence between the tension-disks 116 from which they are led through apertures 117 in a forward extension of the 90 plate 115, over the guide-finger 118 and thence through the eye of the take-up arm 86 87 from which they are led through a guide-aperture 119 in the outer end of the needle-carrying arm 54 to the needle-eyes. 95

In presenting the work for action of the stitch-forming mechanism, the operator grasps the opposite marginal portions of the material to be stitched in tubular form and passes one of such portions along the 100 exterior of the work-supporting member 4 and the other beneath the intermediate frame member 3, bringing them together above the member 4 in their passage beneath the presser-foot. The contraction 105 of the part 4' of the work-supporting member permits the free manipulation of the material in being brought into tubular form, enabling the operator's fingers to freely enter the unstitched article without 110 distorting or enlarging it in its passage to the stitching devices.

The work-supporting member is shown in the drawings provided with a lap-seam folder 120 disposed intermediate the presser-foot and the contracted portion of the work-support. This folder is shown provided with a base-plate 121 secured in position by means of the fastening screw 122.

While the present improvement is shown 120 and described herein in its preferred form, it is evident that it may be materially modified in the construction and arrangement of its component parts within the scope of the present invention.

Having thus set forth the nature of the invention, what I claim herein is:—

1. A sewing machine constructed with a frame comprising a standard, an intermediate member extending laterally therefrom 130

and spaced above the base thereof, and a lateral work-supporting member sustained by said intermediate member and disposed transversely to and laterally offset from said standard with the lower side and the ends thereof exposed and unobstructed for free movement of tubular articles to, along and from the same, said member sustaining a loop-taker in its end portion farthest from the standard and being contracted in girth between such portion and the opposite end, and feeding mechanism incorporated in said frame and adapted to feed the work off the free end of said arm.

2. A sewing machine constructed with a frame comprising a standard, an intermediate member extending laterally therefrom and spaced above the base thereof, and a lateral work-supporting member sustained by said intermediate member and disposed transversely to and laterally offset from said standard with the lower side and the ends thereof exposed and unobstructed for free movement of tubular articles to, along and from the same, said member sustaining a loop-taker in its end portion farthest from the standard and being contracted in both width and depth between such portion and the opposite end, and feeding mechanism incorporated in said frame and adapted to feed the work off the free end of said arm.

3. A sewing machine constructed with a frame composed exclusively of an upright member or standard, a lateral or intermediate member connected therewith and extending outwardly therefrom and spaced above its base, and a lateral work-supporting member depending from said intermediate member and disposed transversely to both of the other members with a clear space above the plane of the base of the standard, said work-supporting member being smaller in girth adjacent its junction with the intermediate member than at the opposite end, stitch-forming and feeding mechanism incorporated in said frame, said feeding mechanism being adapted to feed the work off the free end of said arm.

4. A sewing machine constructed with a frame composed exclusively of an upright member or standard, a lateral or intermediate member connected therewith and extending outwardly therefrom and spaced above its base, and a lateral work-supporting member depending from said intermediate member and disposed transversely to both of the other members with a clear space above the plane of the base of the standard, said work-supporting member being of less width and depth adjacent its junction with the intermediate member than at the opposite end, stitch-forming and feeding mechanism incorporated in said frame, said feeding mechanism being adapted to feed the work off the free end of said arm.

5. A sewing machine constructed with a frame comprising a standard and a lateral arm including a work-supporting member offset from and extending in a direction transverse to said standard, said work-supporting member being contracted in width in that portion nearest its connection with the standard and constructed in the portion beyond the same with a laterally movable section, a reciprocating needle, and a loop-taker mounted in said section and coöperating with said needle.

6. A sewing machine constructed with a frame comprising a standard and a lateral arm including a work-supporting member offset from and extending in a direction transverse to said standard, said work-supporting member being contracted in width in that portion nearest its connection with the standard and constructed in the portion beyond the same with a plurality of reciprocally movable sections, a plurality of reciprocating needles, and loop-takers coöperating with said needles and mounted each in its respective section of the work-support.

7. A sewing machine constructed with a frame comprising a standard and a work-supporting member offset from and extending in a direction transverse thereto and formed with laterally contracted and uncontracted end portions, with the uncontracted portion constructed with a laterally movable section, an actuating shaft journaled in the body portion of said work-supporting member and provided with a driving gear, a loop-taker sustained within said section and having connected therewith a pinion maintained in permanent intermeshing relation with said gear of the actuating shaft, and a reciprocating needle with which said loop-taker coöperates.

8. A sewing machine constructed with a frame comprising a standard and a work-supporting member offset from and extending in a direction transverse thereto and formed with laterally contracted and uncontracted end portions, with the uncontracted portion constructed with a plurality of reciprocally movable sections, an actuating shaft journaled in the body portion of said work-supporting member and provided with a driving gear, loop-takers sustained within the respective sections and each having connected therewith a pinion maintained in permanent intermeshing relation with said gear of the actuating shaft, and a plurality of reciprocating needles with which said loop-takers coöperate.

9. A sewing machine constructed with a frame comprising a standard and a lateral arm including a work-supporting member offset from and extending in a direction transverse to said standard, said work-supporting member being contracted in width in that portion nearest its connection with

the standard and constructed in the portion beyond the same with a laterally movable section, a reciprocating needle, a loop-taker mounted in said section and coöperating 5 with said needle, and means whereby the loop-taker may be adjusted in a direction crosswise of the work-supporting member.

10. A sewing machine constructed with a frame comprising a standard and a lateral arm including a work-supporting member offset from and extending in a direction transverse to said standard, said work-supporting member being contracted in width in that portion nearest its connection with the standard and constructed in the portion beyond the same with a laterally movable section, a reciprocating needle, a loop-taker mounted in said section and coöperating with said needle, and means whereby the loop-taker may 20 be adjusted in a direction substantially parallel with the needle-path.

11. A sewing machine constructed with a frame comprising a standard, an intermediate member extending laterally therefrom and spaced above the base thereof, and a work-supporting member sustained by the intermediate member and offset from and extending in a direction transverse to said standard, a presser-foot opposed to the face 30 of the work-supporting member in the portion thereof farthest from the intermediate member, and a support for said presser-foot movably mounted on the intermediate member and extending therefrom at an inclination to and spaced above the work-supporting member.

12. A sewing machine constructed with a frame comprising a standard, an intermediate member extending laterally therefrom and spaced above the base thereof, and a work-supporting member sustained by the intermediate member and offset from and extending in a direction transverse to said standard, a presser-foot opposed to the face 40 of the work-supporting member in the portion thereof farthest from the intermediate member, a rock-shaft journaled within and lengthwise of the intermediate member, and a presser-foot supporting arm fixed upon 45 said rock-shaft and extending therefrom in a direction inclined to the work-supporting member.

13. A sewing machine constructed with a frame comprising a standard, an intermediate member extending laterally therefrom and spaced above the base thereof, and a work-supporting member sustained by the intermediate member and offset from and extending in a direction transverse to said 50 standard, a presser-foot opposed to the face of the work-supporting member in the portion thereof farthest from the intermediate member, a rock-shaft journaled within and lengthwise of the intermediate member and 55 provided with a tappet-arm, a presser-foot

supporting arm fixed upon said rock-shaft, a spring applied to said tappet-arm for forcing the presser-foot downwardly, and presser-foot lifting means connected with said rock-shaft.

14. A sewing machine constructed with a frame comprising a standard, an intermediate member extending laterally therefrom and spaced above the base thereof, and a work-supporting member sustained by the intermediate member and offset from and extending in a direction transverse to said standard, a presser-foot opposed to the face of the work-supporting member in the portion thereof farthest from the intermediate member, a rock-shaft journaled within and lengthwise of the intermediate member and provided with a tappet-arm, a presser-foot supporting arm fixed upon said rock-shaft, a plunger-pin mounted within a suitable 85 socket disposed transversely of the intermediate frame member and engaging said tappet-arm, a spring applied to said plunger-pin within said socket, and presser-foot lifting means connected with said rock-shaft. 90

15. In a sewing machine, the combination with a shaft provided with an actuating element, of a reciprocating needle, a loop-taker coöperating therewith, feeding mechanism including a feed-dog, means including a common element engaging said actuating element and connected with said needle and with said feeding mechanism for imparting to the needle its reciprocating movements and to the feed-dog its work-advancing and 100 rising-and-falling movements, and a connection between said shaft and the loop-taker for imparting operative movements to the latter.

16. In a sewing machine, the combination 105 with a frame comprising a standard, an intermediate member extending laterally therefrom and spaced above the base thereof, and a work-supporting member sustained by the intermediate member and offset from 110 and extending in a direction transverse to said standard, of a rotary shaft journaled in and longitudinally of said intermediate member and provided with an actuating element, a reciprocating needle and a coöperating loop-taker, feeding mechanism including a feed-dog mounted within said work-supporting member, means including a common element engaging said actuating element and connected with said needle and 115 with said feeding mechanism for imparting to the needle its reciprocating movements and to the feed-dog its work-advancing and rising-and-falling movements, and a connection extending through the work-supporting member between said shaft and the loop-taker for imparting operative movements to the latter. 125

17. In a sewing machine, the combination 130 with a rotary shaft and an actuating eccentric

tric mounted thereon, of a reciprocating needle, a loop-taker coöperating therewith, a feed-dog, a sleeve embracing said eccentric, a connection between said sleeve and said 5 needle and said feed-dog for imparting to the needle its reciprocating movements and to the feed-dog rising-and-falling movements, an independent connection between said sleeve and feed-dog for imparting to 10 the latter work-advancing movements, and loop-taker actuating means.

18. In a sewing machine, the combination with a rotary shaft and an actuating eccentric mounted thereon, of a reciprocating 15 needle, a vibratory arm carrying the same, a loop-taker coöperating with said needle, a feed-dog, a sleeve embracing said eccentric, a sliding pin-and-socket connection between 20 said sleeve and the needle-carrying arm for imparting operative movements thereto, a connection between said needle-carrying arm and the feed-dog for imparting rising-and-falling movements to the latter, means including a sliding pin-and-socket connection 25 between said sleeve and the feed-dog for imparting to the latter work-advancing movements, and loop-taker actuating means.

19. A sewing machine constructed with a frame comprising a standard and a work- 30 supporting member offset from and extending in a direction transverse thereto and formed with a laterally swinging section, an actuating shaft journaled in the body portion of said work-supporting member and 35 provided with a driving gear, a loop-taker sustained within said section and having connected therewith a pinion meshing with said gear of the actuating shaft, a fulcrum for said section having its axis passing 40 through the intermeshing point of the driving gear with said pinion, and a reciprocating needle with which said loop-taker coöperates.

20. In a sewing machine, the combination 45 with a shaft provided at its extremity with an eccentric, of a reciprocating needle, a loop-taker coöperating therewith, feeding mechanism including a feed-dog, a take-up arm, operative connections with said eccentric 50 for imparting reciprocatory movements to the needle, work-advancing and rising-and-falling movements to the feed-dog, and vibratory movements to the take-up arm, and a connection between said shaft and the 55 loop-taker for imparting to the latter operative movements.

21. In a sewing machine, the combination 60 with a shaft provided at its extremity with an eccentric carrying a crank-pin upon its outer face, of a reciprocating needle, a loop-taker coöperating therewith, feeding mechanism including a feed-dog, a vibratory take-up arm mounted upon a fixed fulcrum, a sleeve embracing said eccentric, operative 65 connections, including pin-and-socket joints,

with said sleeve for imparting reciprocatory movements to the needle, and work-advancing and rising-and-falling movements to the feed-dog, a sliding and pivotal connection between said crank-pin and the take-up arm, 70 and a connection between said shaft and the loop-taker for imparting to the latter operative movements.

22. In a sewing machine, the combination with a frame comprising a standard, an intermediate member extending laterally therefrom and spaced above the base thereof, and a work-supporting member sustained by the intermediate member and offset from 75 and extending in a direction transverse to 80 said standard, of a rotary shaft journaled in and longitudinally of said intermediate member and provided at its extremity adjacent the junction of the latter with the work-supporting member with an actuating element, a reciprocating needle, a loop-taker disposed within the end of the work-supporting member farthest from the intermediate member and coöperating with the needle in the production of stitches, feeding 85 mechanism including a feed-dog disposed within said work-supporting member, means including a common element operatively engaging said actuating element for imparting to the needle its reciprocatory movements 90 and to the feed-dog work-advancing and rising-and-falling movements, and a connection extending from said shaft through the work-supporting member to the loop-taker for 95 actuating the latter.

23. In a sewing machine, the combination with a frame comprising a standard, an intermediate member extending laterally therefrom and spaced above the base thereof, and a work-supporting member sustained by 100 the intermediate member and offset from and extending in a direction transverse to 105 said standard, of a rotary shaft journaled in and longitudinally of said intermediate member and provided at its extremity adjacent the junction of the latter with the work-supporting member with an actuating element, a reciprocating needle, a loop-taker disposed within the end of the work-supporting member farthest from the intermediate member and coöperating with the needle in the production of stitches, feeding 110 mechanism including a feed-dog disposed within said work-supporting member, a vibratory take-up arm mounted upon a fixed 115 fulcrum adjacent the junction of the intermediate member with the work-supporting member, means including a common element operatively engaging said actuating element for imparting to the needle its reciprocatory 120 movements and to the feed-dog work-advancing and rising and falling movements, an independent connection between the actuating element and the take-up arm for imparting vibratory movements thereto, and 125 130

a connection extending from said shaft through the work-supporting member to the loop-taker for actuating the latter.

24. In a sewing machine, the combination with a frame comprising a standard, an intermediate member extending laterally therefrom and spaced above the base thereof, and a work-supporting member sustained by the intermediate member and offset from and extending in a direction transverse to said standard, of a rotary shaft journaled in and longitudinally of said intermediate member and provided at its extremity adjacent the junction of the latter with the work-supporting member with an actuating element, a reciprocating needle, a loop-taker disposed within the end of the work-supporting member farthest from the intermediate member and coöperating with the needle in the production of stitches, feeding mechanism including a feed-dog disposed

within said work-supporting member adjacent the loop-taker, means including a common element operatively engaging said actuating element for imparting to the needle its reciprocatory movements and to the feed-dog work-advancing and rising-and-falling movements, a shaft journaled within and longitudinally of the work-supporting member and operatively connected with the loop-taker for actuating the latter, and an intermediate shaft connected at opposite ends by gearing respectively with the above named shafts.

In testimony whereof, I have signed my name to this specification, in the presence of two subscribing witnesses.

ALBERT H. DE VOE.
